The ornamental design for a fin for a vehicle, as shown and described.

DESCRIPTION

This application contains subject matter related to the following co-pending U.S. design patent application:

Application Ser. No. 29/747,493, filed herewith and entitled “Vehicle, Toy, and/or Replicas Thereof”.

FIG. 1 is a top view of a fin for a vehicle according to the design;

FIG. 2 is a top, front perspective view thereof;

FIG. 3 is a bottom, rear perspective view thereof;

FIG. 4 is a right side view thereof;

FIG. 5 is a front view thereof;

FIG. 6 is a rear view thereof; and,

FIG. 7 is a bottom view thereof.

The broken lines illustrate portions of the fin for a vehicle which form no part of the claimed design.
